SOUND REPRODUCING APPARATUS

Herbert Belar, Philadelphia, Pa., assignor to
 Radio Corporation of America, a corporation
 of Delaware

Application December 29, 1939, Serial No. 311,508

8 Claims. (Cl. 179—100.3)

This invention relates to sound reproducing apparatus and more particularly to an improved circuit arrangement for changing from standard sound reproduction to push-pull or vice versa.

In push-pull reproduction, as heretofore manufactured and particularly in such apparatus designed for switching between push-pull reproduction and the standard or single reproduction, there has usually been a change in volume level between the different types of reproduction and the amount of this change has in most instances been as great as 6 db. Such circuits also have required the use of resistors, condensers and other similar circuit elements within the soundhead which has been a great disadvantage for the reason that these circuit elements became spattered with oil and accumulated dust thereby changing their values and when repairs were necessary on a soundhead for mechanical reasons, the delicate circuit elements were readily damaged.

In the improved circuit arrangement of the present invention, no resistors or capacitors are necessary in the soundhead and the balancing potentiometer which is particularly susceptible to the effects of oil or dust is located in the control unit remote from the soundhead, the only critical element remaining in the soundhead being a transformer which is readily encased and shielded and the change-over switch which is of sufficiently rugged construction to give no mechanical trouble will cause no electrical trouble.

The purposes of this invention are accomplished by a novel circuit arrangement in which each of the photocells operates through the entire primary winding of the transformer whether they are connected in push-pull or parallel.

One object of the invention is to provide an improved photocell circuit.

Another object is to provide an improved circuit for change-over from push-pull to standard or vice versa in which there is no change in volume level between the two types of reproduction.

Another object of the invention is an improved sound reproducing circuit in which no critical circuit elements are located in the soundhead.

Other and incidental objects of the invention will be apparent to those skilled in the art from a reading of the following specification and an inspection of the accompanying drawing in which:

Figure 1 is a schematic diagram of the connections in one soundhead and of the corresponding connections in the control unit.

Figure 2 is a schematic diagram of the connections of the apparatus shown in Figure 1 when the switch is in the position for ordinary sound reproduction, and

5 Figure 3 is a schematic diagram of the connections of the apparatus shown in Figure 1 when the switch is in the position for push-pull reproduction.

In the several figures of the drawing which 10 represent different aspects of the same apparatus, the same parts are represented by corresponding reference numerals and in the following description no distinction is made between the reference numerals as applied to the several 15 figures.

The soundhead is generally indicated at 10, and the apparatus indicated within the outline is that which is located within the soundhead while the sound control unit which may be located 20 on the wall or at any other convenient position remote from the soundhead is generally indicated at 11 and the apparatus pertaining to a single soundhead is indicated as being located therein. It should be understood that the sound control unit includes the apparatus for controlling as many soundheads as there may be in the particular installation, and it may also include all of the change-over equipment for the installation and such other control equipment as may 25 be necessary. For each soundhead there will be provided in the sound control unit a duplicate of the apparatus indicated in Figure 1.

The photocells are indicated at 12 and 13 and although two separate photocells are indicated, 30 it should be understood that a single photocell having a plurality of cathodes may be used, such as for example, the type commercially known as the RCA No. 920. If such a photocell is used, the separate photocells referred to hereinafter should be construed as referring to the respective electrodes of the push-pull cell. The cell 12 is permanently connected to one end of the primary winding of the transformer 14 by the lead 22 and the cathode of the cell 12 is also

40 permanently connected to the negative terminal of the B supply through the lead 23. The B supply as it is generally known but which may be otherwise defined as the high voltage direct current supply to the photocells preferably has a 45 value of the order of 90 volts if gas type photocells are used. If separate photocells are used, the voltage may be increased to such a value that 50 90 volts per cell is applied, and if vacuum type photocells are used, the voltage may be considerably in excess of this. When a push-pull gas

type photocell is used, the voltage between any two terminals should not exceed 90 volts at any time.

The cell 13 is connected to the double pole, double throw switch 15 which serves to reverse the connections according to the type of reproduction desired. When the switch 15 is in the position 2, the connections correspond to those shown in Fig. 2 and the photocells are connected to reproduce a standard sound track. The anode lead 24 is connected by the switch 15 to the lead 25 placing it in parallel with the anode of the cell 13. The cathode lead 26 is connected to the cathode connection 23 of the cell 12. As shown in Fig. 2, the two cathodes are then connected to the negative terminal of the B supply while the two anodes are connected through the primary of the transformer 14 to the positive terminal on the potentiometer 16.

When the switch 15 is thrown into the upper position marked 3 in Fig. 1, the connections of the cell 13 are reversed so that it is then connected as shown in Fig. 3. In this case, the cathode of the cell 13 is connected through the leads 26 and 25 to the anode of the cell 12 and thence through the primary of the transformer 14 to the mid-tap of the potentiometer 16. This mid-tap then serves as a negative terminal of the cell 13. The anode of the cell 13 is connected through the lead 24 to the lead 27 going to the positive terminal of the B supply, as shown in Fig. 3. When connected in this fashion the cells must be balanced so as to secure equal output from the two cells and this balancing is accomplished by adjusting the position of the mid-tap of the potentiometer 16.

As shown in Fig. 1, the anode leads of the two photocells are not connected directly to the power supply but are supplied with current through the resistor 17 and 18 which are bypassed respectively by the capacitors 19 and 20. It will be apparent that in the above described apparatus, the direct connection of the photocell electrodes to the transformer avoids the use of either capacitors or resistors located adjacent photocells as shown in my Patent No. 2,178,219, while at the same time retaining all of the advantages of the apparatus described in said patent.

I claim as my invention:

1. In combination, an output transformer, a pair of input devices, and switching means for selectively connecting both of said input devices directly across the entire primary winding of said transformer either in push-pull or in parallel.

2. In combination, an output transformer, a pair of photocells, and switching means for selectively connecting both of said photocells directly across the entire primary winding of said transformer either in push-pull or in parallel.

3. In combination, an output transformer, a

pair of photocells, and switching means for selectively connecting said photocells directly to said transformer either in push-pull or parallel with both of said photocells operating through the entire primary winding of the transformer.

4. In combination, an output transformer, a photocell directly connected to said transformer with its entire a-c output fed through the entire primary of said transformer, a second photocell, and means for selectively connecting said second photocell either in parallel with said first photocell or in a similar manner with its polarity reversed.

5. Sound-reproducing apparatus including in the sound-reproducing unit a pair of photocells, output coupling means and a switch for selectively connecting said photocells in either push-pull or in parallel relation to said coupling unit, and a control unit relatively remote from said sound-reproducing unit including balancing means for said photocells, feed resistors and capacitors bypassing said feed resistors.

6. In combination, an output device, a photocell connected permanently across the entire input circuit of said device, a second photocell, and means selectively connecting said second photocell either in parallel with the first photocell or with one electrode opposite to that of the first photocell connected to said output device and the other electrode connected to a separate power supply.

7. In combination, an output device, a photocell connected permanently directly across the entire input circuit of said device, a second photocell, means selectively connecting said second photocell either in parallel with the first photocell or with one electrode opposite to that of the first photocell connected to said output device and the other electrode connected to a separate power supply terminal, and a potentiometer for supplying current to said photocell, one end terminal and the mid-tap of the potentiometer being connected to the first photocell and the other end terminal constituting said separate power supply terminal.

8. In combination, an output device, a photocell connected permanently thereto, a second photocell, means selectively connecting said second photocell either in parallel with the first photocell or with one electrode opposite to that of the first photocell connected to said output device and the other electrode connected to a separate power supply terminal, a potentiometer for supplying current to said photocell, one end terminal and the mid-tap of the potentiometer being connected to the first photocell and the other end terminal constituting said separate power supply terminal, and resistors shunted by capacitors connecting said mid-tap and the second end terminal to the photocells.

HERBERT BELAR.
